PLAYGROUND APPARATUS SUPPORT

Robert S. Wormser, Hillsdale, Mich., assignor to Game-Time, Inc., a corporation of Michigan

Filed June 5, 1964, Ser. No. 80,296

Term of patent 14 years

(Cl. D34—5)

FIG. 1 is a perspective view of a playground apparatus support showing my new design.

FIG. 2 is a side elevational view thereof, the opposite side being identical thereto, and

FIG. 3 is a front elevational view thereof, the opposite side being identical thereto.

The broken line portions illustrated in FIGS. 1 and 3 are for illustrative purposes only to illustrate an environmental application of my design.

I claim:

The ornamental design for playground apparatus support, as shown and described.
